CONVERTIBLE SOFA BED

Frank Faller, Los Angeles, Calif., assignor to Restwell
Mfg. Co., Los Angeles, Calif., a partnership

Application December 20, 1954, Serial No. 33,605

Term of patent 14 years

(Cl. D15—11)

Fig. 1.

Fig. 2.

*Fig. 3.Fig. 4.*Fig. 1 is a front view in perspective of the convertible sofa bed embodying my new design, the backrest being shown in upright position;

Fig. 2 is a rear view in perspective of the same;

Fig. 3 is an end view of the same, taken in the direction of the arrow 3 upon Fig. 1; and

Fig. 4 is a perspective view of the convertible sofa bed embodying my new design, the backrest being shown in its horizontal position to convert the sofa into a bed.

I claim:

The ornamental design for a convertible sofa bed, as shown.
